EARTH ANCHOR

Harley R. Ogburn, Marshall, Tex.

Application July 6, 1948; Serial No. 37,263

3 Claims. (Cl. 189—92)

1

This invention relates to new and useful improvements in earth anchors.

One object of the invention is to provide an improved expandable earth anchor which may be positioned wherever desired in an opening or hole in the earth and expanded to provide an extremely secure and rigid anchoring means which guy wires and the like may be secured.

A particular object of the invention is to provide a device of the character described wherein the expandable wings of the anchor are positively restrained and confined at all times whereby accidental displacement of one of said wings in the course of setting operations is precluded.

A further object of the invention is to provide an expandable earth anchor of the nature described wherein the inner ends of the expandable wings are positively and rigidly positioned between the upper and lower blocks of the anchor after the latter has been expanded into its set position.

Yet another object of the invention is to provide an improved earth anchor which is extremely simple in structure and economical to manufacture, yet which provides a rugged and dependable anchoring structure.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a side elevation of an earth anchor constructed in accordance with this invention, said anchor being in an unexpanded position.

Fig. 2 is an enlarged, vertical, sectional view of the earth anchor with the expanded position of the anchoring wings indicated in dotted lines.

Fig. 3 is a vertical, sectional view of the anchor in an expanded position.

Fig. 4 is a horizontal, cross-sectional view taken upon the line 4—4 of Fig. 2 and

Fig. 5 is a horizontal, cross-sectional view taken upon the line 5—5 of Fig. 2.

In the drawings, the numeral 10 designates a screw-threaded anchor rod having an integral eye 11 formed upon its upper end. A substantially triangular base or follower block 12 is provided with a central, screw-threaded opening 13 which receives the lower end of the rod 10 so as to secure the follower block 12 thereupon. An integral stud or boss 14 projects laterally from each side of the block 12, said bosses being substantially rectangular in shape and having their longer dimensions extending lengthwise of the lateral faces or sides of the follower block. An elongate recess 15 is cut longitudinally of each of the bosses 14, the bottoms 16 of the recesses being semicylindrical in outline, and said recesses terminating short of the ends of the bosses 14 as illustrated in Fig. 5. A shallower notch or cut-out portion 17 extends from the outer wall of each of the recesses 15 to the outer face of the bosses 14, it being noted that the bottoms of the recesses 17 are positioned in horizontal planes above the lowermost portions of the curved bottoms 16 of the recesses 15.

A plurality of blades 18, commonly called "wings" in this art, are carried upon the follower block 12. Each of the wings is provided with a transverse, cylindrical hub 19 on its lower end, the curvature of said hubs being substantially equal to the curvature of the arcuate or cylindrical bottoms 16 of the recesses 15. The overall length of each of the hubs is slightly less than the length of the recesses 15 whereby the hubs may be inserted into said recesses and have a sliding fit upon the arcuate bottoms thereof. The wings 18 are curved longitudinally in a plain perpendicular to the axes of the hubs 19 and carry integral reinforcing ribs 20 upon their outer faces. The ribs 20 extend longitudinally of the wings and substantially throughout the entire length thereof, and serve to increase the rigidity and strength of the wings.

Adjacent the upper end of the anchor rod 10, a relatively large nut 21 is jammed against the upper end of the screw-threads carried by said rod, whereby the nut may not undergo additional rotation and may be considered as substantially fixed with respect to the anchor rod. Obviously, any sort of an integral lug or enlargement may be provided upon the rod 10 in place of the nut 21. However, the structure described has been found to be economical in manufacture and easy to assemble. An upper spreader or expander block or head 22 jacks against or abuts the under side of the nut 21. In plan, the block 22 has the shape of an irregular hexagon, the sides of the hexagon being alternately long and short; whereupon three long sides 23 of equal length, and three short sides 24, also of equal length, are provided by said spreader or expander block. A marginal flange or skirt 25 depends downwardly and outwardly at an angle from the perimeter of the spreader block, the skirt necessarily having the same general outline, or being similar in shape, to the spreader block. The skirt is thus made up of three relatively long side walls 26 corre-

sponding to the long edges or faces 23, and three relatively short side walls 27 corresponding to the edges 24 of the spreader block. All of the side walls 26 and 27 extend downwardly and outwardly from the central portion of the spreader block, it being understood that the entire structure described, including the spreader block and the walls 26 and 27, is formed in one piece by casting or any other suitable procedure.

An enlarged central opening 28 is provided in the center of the block 22 and receives the screw-threaded portion of the rod 10. Since the opening 28 is somewhat greater in diameter than the rod 10, it permits the spreader structure described to slide freely upon said rod, but at the same time, is not sufficiently large as to permit the spreader block to move upwardly past the retaining nut 21 which bears upon or jacks against the upper surface of said block.

Each of the long side walls 26 of the depending skirt of the spreader block is provided with an elongate slot or opening 29 cut therethrough and extending longitudinally with respect to said side walls. As illustrated in Fig. 4, the shape of the openings 29 is similar to the shape of the side walls 26. The rounded upper ends 30 of the wings 18 are received within the slots or openings 29, and it is pointed out that said slots are of sufficient length as to accommodate the widest portions of the wings 18 which are relatively wide and thin in structure. The openings 29 extend not quite perpendicular to the faces of the side walls 26 and are of a width sufficient only to accommodate the thickness of the wings 18 and the reinforcing ribs 20 as the lengths of said wings move longitudinally through the opening 29.

In assembling this earth anchor, the spreader block is positioned upon the upper portion of the rod 10 immediately beneath the retaining nut 21, and the upper extremities 30 of the wings 18 are engaged within the openings 29. The cylindrical hubs 19 provided upon the lower ends of the wings are placed within the recesses 15, and suitable retaining pins 31 are passed through axial openings 32 provided in the hubs 19, and also through aligned openings 33 formed in the bosses 14. With the base or follower block 12 screwed upon the lower end of the rod 10, the wings are securely held against movement in any direction by reason of the pins 31 and the engagement of the upper ends of the wings within the openings 29. The anchor may now be handled in almost any fashion and may be inserted into and removed from openings in the earth without danger of one of the wings becoming accidentally displaced or dislodged and entangled with the wall of said earth opening. This is highly desirable since it enables the anchor to withstand the rough treatment and handling which devices of this nature customarily receive, and also makes provision for the haphazard and improper methods often employed by workmen in positioning the anchors within the holes in the earth in which the anchor is to be employed. Short of deliberate destruction, it is virtually impossible to displace one of the wings 18 while the device is in its retracted position as illustrated in Fig. 2.

After the hole has been drilled in the earth in which it is desired to position this anchor, the anchor is inserted thereinto in its retracted position and brought to the point at which it is desired to be set. Then, rotation of the rod 10 by engaging said rod or its eye 11 with any suitable tool (not shown) results in movement of the follower block 12 upwardly toward the spreader

block 22. During this operation, the two blocks and the wings are held against rotation by the engagement of the outer edges of the block 22 with the walls of the earth opening, or the engagement of the underside of the block 12 with the bottom of the hole, or both. As the rotation of the rod 10 is continued, the block 12 continues to move upwardly thus bearing against the hubs 19 upon the lower ends of the wings 18 and forcing said wings upwardly with respect to the rod 10 and the spreader block 22. The upward movement of the spreader block is prevented by means of the stop nut 21, but said nut and the operating rod are free to rotate with respect to the spreader block by reason of the enlarged opening 28 and the friction bearing of the stop nut upon the upper surface of said spreader block. In the course of their upward movement, the wings 18 follow an arcuate path representing a continuation of their own longitudinal curvature, and feed outwardly through the openings 29 into the side walls of the earth holes in which the device is positioned. This operation is continued until the anchoring device is in its fully expanded position as illustrated in dotted lines in Fig. 2 and in full lines in Fig. 3. In this position, the hubs 19 are tightly clamped between the arcuate bottoms 16 of the recesses 15 and the underside of a depending, central disk-like element or boss 34 formed integrally on the underside of the spreader block or head 22. In the course of the upward and outward movement of the wings 18, their hubs 19 revolve within the arcuate bottoms 16, so that in the fully expanded position of the anchor, it is one side of each of the hubs 19 which engages the underside of the element 34. The inner ends of the wings are thus securely anchored and clamped against upward or downward movement, and the walls of the openings 29 function as fulcrums to enable the wings to resist upward or downward movement or swinging about the pins 31. During this setting operation, there is no shearing load upon the pins 31 since this force is borne by the hubs 19 and recess bottoms 16.

It is to be noted that the movement of all portions of the wings 18 is controlled at all times, both by the securing of the lower ends of the wings to the base or bottom block 12 and the engagement of said wings within the openings 29. With this structure, accidental displacement of the wings at any time is precluded and the operator has full and absolute control of the handling and positioning of said wings. It is also to be noted that the movement of the wings in an arcuate path, representing a continuation of their own longitudinal curvature, into the earth defining the side wall of the opening in which the anchor is positioned, results in projection of the wings into said earth without undue disturbance thereof and with a minimum of displacement or gouging of said earth. By this means, the setting or expanding of the anchoring device is greatly facilitated with a minimum of effort being necessary to project the wings into their earth engaging position. At the same time, because of the lack of disturbance of the earth, a much more solid and substantial engaging-media for the wings is provided.

In some instances, a workman may fail to expand the anchor completely so that the blades do not have full engagement with the earth. However, the structure of the anchor provides for this contingency in that an upward pull upon the anchor rod, as by securing a guy wire thereto,

will pull the base block 12 upwardly and complete the setting of the anchor.

It is to be noted that the anchor rod may have screw-threaded engagement with either the upper or the lower blocks since all that is necessary is the urging together of the blocks as the anchor is set. Also, the blades may be pivoted to either of the blocks and be expanded by the other. Of course, the embodiment of the invention described is the preferred form because the blades are pressed into the wall of the earth opening without disturbing the surrounding dirt, but this same desirable result may be obtained by inverting the anchor structure.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. An earth anchor including, a base block, a spreader block above the base block, a screw-threaded anchor rod extending through the blocks, one of the blocks having a screw-threaded bore receiving said rod, a plurality of anchor wings, each wing having a substantially cylindrical hub on one end, the axes of the hubs extending across the wings parallel to the transverse axes of the wings and at right angles to the longitudinal axes of the wings, the base block having recesses of arcuate cross-section receiving the hubs, the recesses having semi-cylindrical bottoms of substantially the same radius of curvature as the hubs and in contact with the peripheries thereof, whereby the hubs may revolve in said recesses and are fully supported thereby in all positions, the axes of the recesses being spaced inwardly from the perimeter of the base block, said hubs projecting above the base block, and a centrally located extension on the underside of the spreader block positioned inwardly of the periphery thereof abutting the hubs when the anchor is expanded to hold the hubs in their recesses and to withstand forces tending to move the hubs upwardly.

2. An earth anchor including, a base block, a spreader block, a screw-threaded anchor rod ex-

tending through the base block and the spreader block and having screw-threaded engagement in one of said blocks, means on the rod engaging the other of said blocks to prevent shifting of the latter block upon the rod away from the opposite block, a plurality of anchor wings having relatively wide and thin blades and a substantially cylindrical hub upon one end, the axes of the hubs extending across the wings parallel to the transverse axes of the wings and at right angles to the longitudinal axes of the wings, the base block having recesses of arcuate cross-section receiving the hubs, the recesses having semi-cylindrical bottoms of substantially the same radius of curvature as the hubs and in contact with the peripheries thereof, whereby the hubs may revolve in said recesses and are fully supported thereby in all positions, the axes of the recesses being spaced inwardly from the perimeter of the base block, and a marginal flange upon the spreader block extending toward the base block, said flange having transverse openings within which the free ends of the blades engage, said hubs projecting above the base block, said base block being smaller than the spreader block so as to be received within the marginal flange, the underside of the spreader block having an extension positioned centrally and inwardly of the periphery thereof abutting the upper sides of the hubs when the anchor is expanded.

3. An earth anchor as set forth in claim 2, wherein the openings are only slightly longer and wider than the width and thickness of the blades so that the openings function as guides for the blades, and an extension on the spreader block for engaging the hubs of the wings and holding them within the recesses when the anchor is expanded.
